HOT BOX OIL BURNER

Filed April 2, 1928

Fig. 1.

Fig. 4.

Fig. 2.

Inventor
H.C. Robinson,

By Clarence A. O'Brien
Attorney

UNITED STATES PATENT OFFICE.

HUBERT C. ROBINSON, OF DALLAS, TEXAS.

HOT-BOX OIL BURNER.

Application filed April 2, 1928. Serial No. 266,625.

The present invention relates to a hot box oil burner and the advantages, objects and operation thereof will be apparent when taken in conjunction with the following description 5 and accompanying drawings wherein:

Figure 1 is an elevation of an assembly embodying the features of this invention.

Figure 2 is a sectional view taken substantially on the line 2—2 of Figure 1, and

10 Figure 3 is a detail front elevation of the hot box.

Figure 4 is a detail sectional view of the oil line.

15 Figure 5 is a detail section through the tray pan.

Referring to the drawing in detail, it will be seen that the numeral 5 denotes a conventional steam cleaner to which my improved fire box 6 is attached by flanges 7. The front

20 wall of this fire box is provided with an opening over which is a pivoted closure 8. The top of the fire box is provided with an opening 9. An inverted V-shaped bracket 10 rises from the top across the opening 6 and has a

25 clamp 11 at its apex. The numeral 12 denotes an oil tank from which extends the fuel pipe 14 through a heating drum 15 of the steam cleaner 5 downwardly through the bearing 14' in the clamp 11.

30 A valve 16 is incorporated in the pipe 14. A shaft 17 is mounted in the box 6 to rise upwardly and centrally through the opening 9, and terminates in the lower extremity of the bearing 14'. Within the box there is jour-

35 naled on this shaft a spray fan 18.

Considerable trouble has been experienced with steam cleaners on account of not having enough heat to carry the amount of steam re-

quired for cleaning purposes which is usually

40 about fifty pounds.

Any kind of fuel may be utilized and I have had considerable success with reclaiming heavy oil. This burner may be used on any wood or coal stove. To operate the burner a

45 piece of waste paper or rag with some oil on it is set on fire and dropped into the box 6, through the opening in the front wall thereof by swinging the closure 8 out of the way. The closure is put back to place and a small

50 amount of oil is adapted to flow through the pipe by opening the valve 16. This oil should not flow faster than to cause more than a

steady dropping. In doing this the fan does not turn until the box gets hot, which usually requires from two to three minutes. The fan 55 is then released and more oil is turned on which will increase as the heat increases, the speed of the fan also increasing which forms a spray of the oil. This oil flows through the pipe 14 down the fan shaft to the fan and 60 there combustion takes place. The oil from the pipe 14 passes into the bearing 14' and then flows down the outside of the shaft 17 onto the fan blades, which cause the oil to be sprayed out centrifugally. When the fire is 65 started in the box, a draft is created to rise through the opening 9 and thereby causing the fan to turn and the oil flows down the shaft 17 to the fan and is sprayed out into the box. After the burner becomes properly 70 heated and the flow of oil is regulated properly, there is very little smoke and the largest part of the time there is no smoke at all.

It is apparent that changes in the details of construction, and in the combination and 75 arrangement of parts may be resorted to, without departing from the spirit or scope of the invention or sacrificing any of its advantages.

Having thus described my invention, what 80 I claim as new is:

1. A hot box oil burner comprising a box with an opening in the top thereof, an opening in one side wall thereof, a closure for the opening in the side wall, a shaft extending 85 into the box and having a fan thereon within the box, and a fuel line leading to the shaft, said shaft being journaled in the fuel line and a bracket rising from the box and holding the lower end of the fuel line. 90

2. In combination with a steam cleaner, a fire box fixed to the lower portion thereof and having an opening in one side wall, a closure associated therewith, and an opening in the top thereof, a bracket rising from the top of 95 the fire box, a fuel line supported in the bracket, a shaft journaled in the lower end of the fuel line and extending through the opening in the top of the box, a spray fan on the lower end of the shaft within the box, and a 100 fuel line tank to which the line is attached.

In testimony whereof I affix my signature.

HUBERT C. ROBINSON.
